(57) **CLAIM**

The ornamental design for an apparatus to control fluid flow
through a tube, as shown and described.

DESCRIPTION

FIG. 1 is a front, bottom, and right side perspective view of
the apparatus to control fluid flow through a tube, showing
my new design;

FIG. 2 is a front, top, and left side perspective view thereof;

FIG. 3 is a bottom plan view thereof;

FIG. 4 is a top plan view thereof;

FIG. 5 is a left side elevational view thereof;

FIG. 6 is a right side elevational view thereof;

FIG. 7 is a front side elevational view thereof; and,

FIG. 8 is a back side elevational view thereof.

The broken lines shown in the figures represent portions of
the apparatus to control fluid flow through a tube that form
no part of the claimed design.

A broken line shown is a boundary line between the top
portion and the body of the apparatus.
